INVENTOR

Horace H. Holmes

United States Patent Office.

HORACE H. HOLMES, OF ELMIRA, NEW YORK, ASSIGNOR TO HIMSELF, J. D. DALE, IRA S. BEERS, AND J. H. DALE.

Letters Patent No. 99,318, dated February 1, 1870.

IMPROVED RAILWAY-CAR REPLACER.

The Schedule referred to in these Letters Patent and making part of the same.

Be it known that I, HORACE H. HOLMES, of the city of Elmira, county of Chemung, and State of New York, have invented a new and useful Device for Putting Cars upon the Track; and I do hereby declare that the following is a full and exact description of the construction and operation of the same, reference being had to the annexed drawings, making part of this specification, in which—

Figure 1 is a perspective of switch as it is used.

Figure 2 is a plan of the same.

Figure 3 is a view of rail, with swivel.

Figure 4 is a view of the end of wedge and rail.

To enable others skilled in the art to make and use my invention, I will proceed to describe its construction and operation.

I make two wedges, A A', shown in fig. 1, of about two feet in length and eight inches in width, of wood or other material, so as to put them between the truck-wheels of a car. They are covered with iron, C C, figs. 1, 2, and 4, of suitable thickness, and of sufficient strength to sustain the weight.

I use one plane wedge, A', on the inside of track, for the flange of the car-wheel to run on, and in thickness I make it half an inch lower than the top of the track when it is in place, thus preventing the wheel from running over and off on the other side of the track, which is liable to happen to other arrangements used for the same purpose. The other wedge, A, figs. 1 and 2, is made as thick as the rail is high, and of the same length as A'.

I place wedge A on the outside of rail or track, and against the same.

Wedge A is provided with an adjustable rail, B, figs. 1 and 2, thick enough for the tread of the wheel to run on.

Adjustable rail B guides the wheels of the truck on the track without difficulty.

Lower end of rail B is chamfered, while the upper end is provided with a swivel, D, shown in figs. 2, 3, and 4, with a flange, F F, fig. 4, projecting down, that fits the track, and by turning it from one side to the other of wedge A, it can be used on either the right or left side of track, so that the same device may be used to replace a car upon the track, no matter whether it is upon the right or left.

At the centre of rail B, is a bolt, E, that secures it to wedge A, and is sufficiently free to allow it to be moved from one side of wedge A to the other, so that it may be used either right or left.

The swivel D, figs. 2, 3, and 4, has flanges F F, fig. 4, which project down, and fit track, preventing adjustable rail from moving while the wheels are being drawn on or replaced upon the track.

It will be seen that a car, in this way, can be put upon the track in a few moments.

What I claim as new, and desire to secure by Letters Patent, is—

1. A portable switch or car-replacer, composed of a wooden wedge, A, covered on both sides with sheet-metal, and provided with the pivoted rail B and swivel D, attached thereto, all constructed and arranged to operate as and for the purpose set forth.

2. In combination with the above, the wedge A, constructed and arranged as and for the purpose set forth.

HORACE H. HOLMES.
